UNITED STATES PATENT OFFICE

153,802

DESIGN FOR A VENDING MACHINE
HOUSING

Clarence A. Hokinson, Chicago, Ill.

Application December 18, 1947, Serial No. 143,206

Term of patent 3½ years

(Cl. D52—3)

To all whom it may concern:

Be it known that I, Clarence A. Hokinson, a citizen of the United States, residing at Chicago, in the county of Cook and State of Illinois, have invented a new, original, and ornamental Design for a Vending Machine Housing, of which the following is a specification, reference being had to the accompanying drawing, forming part thereof.

Fig. 1 is a front elevational view of a vending machine housing, showing my new design;

Fig. 2 is a side elevational view;

Fig. 3 is an enlarged cross section on the line 3—3 of Fig. 1; and

Fig. 4 is a similar fragmental section on the line 4—4 of Fig. 1.

The essential features of my design reside in the portion shown in full lines.

I claim:

The ornamental design for a vending machine housing, as shown and described.

CLARENCE A. HOKINSON.
